DESIGN FOR A BOTTLE

John Joseph Musselman, Watertown, N. Y.

Application December 3, 1938, Serial No. 81,560

Term of patent 14 years

To all whom it may concern:

Be it known that I, John Joseph Musselman, a citizen of the United States, residing at Watertown, county of Jefferson, State of New York, have invented a new, original, and ornamental Design for Bottles, of which the following is a specification, reference being had to the accompanying drawing, forming a part thereof.

Fig. 1 is a side view of a bottle showing my new design;

Fig. 2 is a plan view thereof.

I claim:

The ornamental design for a bottle, as shown.

JOHN JOSEPH MUSSELMAN.
